[57] CLAIM

The ornamental design for side panel for ceiling lights, as shown and described.

DESCRIPTION

FIG. 1 is a front perspective view of a side panel for ceiling lights showing my new design;

FIG. 2 is a rear perspective view thereof; and

FIG. 3 is an end view thereof.

The end not shown is similar to the end shown.

The side panel is broken away in FIGS. 1 and 2 to indicate indeterminate length.
